DES N° 1113

7-5-1859

Des. 113

James Greer & Rufus J. King, of Dayton, Ohio.
Letters Patent No. 113, B. Dated July 5, 1859.

The schedule referred to in these Letters Patent, and making part of the same.

To all whom it may concern:

Be it known that we James Greer & Rufus J. King, both of Dayton Montgomery County, Ohio, have invented a certain new & original design for the side and doors of a Cooking Stove, which we call the "Rover" and we hereby declare that the same is represented in the accompanying drawings which are made a part of this Specification and in which

Fig. 1. is a side view, and

Fig. 2, a vertical section.

We claim as new and of our invention herein and desire to secure by Letters Patent,

The design exhibited in the accompanying drawings, for the side and doors of a Cooking Stove.

In testimony of which invention, we hereunto set our hands.
